13 Claims. (Cl. 9—304)

This invention appertains to improvements in swimming appliances for use in rendering swimming easier and increasing the rate of movement of a swimmer in the water.

With increased interest in swimming, there is a present need for mechanical means not only to make swimming less taxing and effortless but also to enable the art of swimming to be taught easier and more effectively to beginners. Further, with the new interest in underwater swimming, especially spear fishing, there is a need for mechanical swimming appliances that will increase the rate of movement of a swimmer both on and under the water.

There are many types of known swimmers' appliances, but none of such known constructions provides a potential propulsive force for forward thrust on each stroke of the leg. None of the known swimming devices is designed for two-way strokes of approximately equal propulsion force. While some of the devices included paddles or the like which were hinged or pivotally attached to the feet of a swimmer, such paddles provided a propulsion action on only one stroke of the leg and were hinged or pivoted for the sole reason to lessen the water resistance on the return stroke in preparation for the next propulsion stroke. Further, such prior devices were cumbersome and were tiring in use due to two factors viz. (1) inability to use such devices while executing proper leg strokes and necessity to alter proper leg movements to bring such devices into play as propulsion factors and (2) positioning of center of pressure in such devices out forward of the ball of the foot and, in most instances, out beyond the toes.

Of late, rubber swim-fins have been designed and such devices generally include foot receiving portions and fin sections that project forwardly of such portions and extend outwardly beyond the toes. Such fins, while comfortable, due to their lightness, are not entirely effective since they have a limited working area, such working area is mainly beyond the toes of the foot and such devices lack a two-stroke or two-cycle thrust action, since only on one stroke of the leg can any propulsion force be obtained, the return stroke of the leg finding such fins merely treading water in their return to the start of the propulsion stroke.

It is, therefore, the primary aim and purpose of this invention to provide a swimming fin that will give a forward thrust on each stroke of the leg, such fin possessing a two-cycle or two-stroke action so that on each stroke of the leg, a forward thrust of equal magnitude is produced by the fins.

Another object of this invention is to provide a swimming fin which is pivotally mounted on the foot of a swimmer in such a way that the center of pressure of the fin is located at the ball of the foot.

A further object of this invention is to provide a swimming fin that is hydrodynamically designed to be driven through the water in a course at the best angle of attack

2

to the line of swimming progress and which has a reciprocating two-cycle action to produce equal forward thrust from each of the two-way strokes of the legs in executing such strokes as the flutter.

5 A further object of this invention is to provide a streamlined, lightweight and sturdy fin structure which can be comfortably used in the water, without any extra physical effort and which can be worn while walking on land and on the bottom of the water without impeding or interfering with natural walking motion.

The foregoing and ancillary objects, including economy of production and ease of use plus interchangeability of the fins from one foot to the other, are obtained by this invention, the best known form of which is described in the following description and illustrated in the accompanying drawings, wherein;

Fig. 1 is a side elevational view of the swimming fin device showing it attached to the foot;

Fig. 2 is a vertical cross-sectional view taken on line 2—2 of Fig. 1;

Fig. 3 is a top plan view thereof with a fence forming water path shown formed on the fin and

Fig. 4 is a side elevational view of Fig. 3.

Referring now more particularly to the drawing, the numeral 10 generally designates the swimming fin of the present invention with the fin being adapted to be attached to each foot of the user.

With the designing of the fins 10, an effective fish-tail action has been accomplished. In other words, an effective two-way reciprocating fish-tail action has been accomplished. The action of the fish-tail propulsion principle, which is seen in nature in sailfish, swordfish and other fish, enables the swimmer to achieve a greater rate of movement than is possible with the naked feet.

The fins 10 are positioned to extend laterally from both sides or one side of the foot and may be disposed in a plane coincident with the bottom of the foot or in parallel planes to the bottom of the foot at points vertically thereabove. The fins are pivoted to the foot for pivotal movement about the axis a—a, which is contained in a plane that transversely intersects the ball of the foot. The line x—x represents the center of water pressure of the fins, such center of pressure being across the ball of the foot and disposed adjacent to and just forwardly of the axis a—a.

The fins have upper and lower working surfaces 14 and 16 which provides a two-cycle reciprocating motion of the fins about the axis a—a, such axis being particularly disposed relative to the foot to place the working surfaces at the correct angle of attack for each stroke of the alternating reciprocating motion of the legs. The center of resistance for both strokes is maintained at the point x—x and is disposed approximately at the ball of the foot. The fins are balanced due to the fact that the center of pressure is just slightly forward of the axis a—a and thereby, lost motion is reduced to a minimum since very little of each reciprocating stroke of the fins is wasted while the fin is swung by water pressure to its normal position as shown in Figure 6, wherein the two positions of the fin under the up and down stroke of the legs is shown. The fins, due to the pivotal axis in relation to the ball of the foot and the center of pressure in relation to the ball of the foot and its closeness to such axis, are designed to be driven through the water in a course at the best angle of attack to the line of swimming progress. It is to be particularly appreciated that the pivotal movement of the fins is not an idling swivelling action for the purpose of lessening the water resistance on the return stroke in preparation for the next propulsion stroke as is true in prior art constructions.

Conversely, the pivotal mounting of the fins is for the specific purpose of obtaining the reciprocating, 65

two-cycle action of the fins in achieving an effective two-way reciprocating fish-tail action.

The fins are pivoted to a foot receiving means, one form of which is shown for exemplary purposes in Figs. 1-4 and is indicated by the reference numeral 18. Such form of foot receiving means, as illustrated, is merely exemplary, since with the mounting of the fins at various vertically spaced points relative to the bottom of the foot, it is obvious that various changes in the foot receiving means would be dictated.

The foot receiving means 18 includes a U-shaped member 20 which may be formed from plastic or aluminum light weight, inexpensive and sturdy material. The U-shaped member 20 includes a support for the fin 10, shown in Figs. 1 and 2 and serves as the means for pivotally supporting the fin. The member 20 includes a flat web portion 22, which is positioned beneath the bottom of the foot 24 and is flat. The web portion 22 preferably extends from a position just forward of the falanges of the toes and terminates rearwardly at a point just rearward of the arch of the foot. Obviously, such axial length of the web portion 22 is primarily for comfort, when the user is walking on land or wading on the bottom of a water body with the swimming device attached. However, there is an additional factor which dictates the axial length of the web portion 22 and such factor is the comfortable use of the device while swimming. In this respect, the propulsive thrust force of the fin 10 will have no effect on the muscles of the foot due to the firm support afforded by the web portion 22. Also such portion strengthens the bottom of the foot and affords a firm protective surface therefor, when such portion of the foot is itself effecting a propulsion force, coincident with the return stroke of the leg.

Integrally formed with the opposing longitudinal side edges of the web portion and positioned intermediate the ends thereof are upstanding sides 24 and 26. Such sides are disposed alongside the ball of the foot and terminate in reduced upper ends 28 and 30. The fin 10 is formed on its underside or, speaking in terms of the fin in use, on the upper working surface 14 with apertured ears 32 and 34. Such ears are disposed parallel to the sides 24 and 26, the ear 32 lying alongside the upper end of the side 30 and being pivoted thereto by a suitable pivot pin 36. The ear 34 is spaced laterally from the side 28 and is pivoted thereto by a pivot pin 38. The spacing of the ear 34 from the side 28 is for the purpose of providing a space for the spring 40 which is coiled on the shank of the pin 38 intermediate the ear 34 and the side 28. The spring 40 has one end suitably anchored to the ear 34 and its opposite end suitably anchored to the side 26 and functions solely to retain the fin in a plane parallel to the web 22 or, otherwise stated, to the bottom of the foot 24 when the wearer is walking. In other words, the purpose of the spring is to prevent the fin from dropping downward at its extending end and interfering with the normal walking movement of the foot. For this reason, it may be desirable to have the sides 24 and 26, whose sole function is to space the fin 10 vertically above the foot, position the fin a few inches above the ground so as not to interfere with the normal walking motion. With respect to the rested position of the fin, which is illustrated in Figs. 1 and 2, and for which purpose the spring 40 is provided, it is to be noted that the sides 24 and 26 terminate at their upper free ends in squared terminal points so that the working surface 14 can rest flatly in a horizontal plane on the sides, the fin being retained thereon by the spring 40.

An elastic or otherwise deformable foot encircling band 42 has its ends suitably attached by fasteners 44 to the juncture point of the side edges of the web and the sides 24 and 26. Such band, as shown in Figs. 1 and 2, is formed so that the foot can be placed on the top of the web 22 and moved forward into the open end of the band which will snugly fit over the instep. A heel

encircling strap 46 is suitably attached to the band 42 as by passing it through slots 48 in the band. The strap is adjustable in length and provided with a buckle or other suitable fastener means so that it can be adjustably fitted to the heel. It is to be particularly noted from a consideration of Figure 1, that the pivots 36 and 38 are disposed forwardly of the rear edges of the sides and that the pivots pivotally mount the fin 10 so that the fin pivots about an axis which is contained in a plane that transversely intersects the ball of the foot. It is to be also noted that the major portion of the fin is disposed forwardly of such axis and that, therefore, the center of water pressure is along the line x-x or immediately forward of the pivot or axis.

15 The fin 10, as shown in the drawings, includes two side sections 50 and 52, which are formed integrally with a connecting center section 54. The center section 54 is considerably reduced in width from the side sections and has concave rear and forward edges. The purpose 20 of providing the relatively narrow center section 54 and having the forward and rear edges thereof concave is to permit the side sections 50 and 52 to function in the pivotal movement of the fin without any interference from the toes or instep. Obviously, if the fins were 25 positioned below the instep, that is extending laterally from the sides of the foot or from the bottom of the foot, the center section 54 would be dispensed with and the two side sections would be separately constructed and separately mounted, though they would have a common pivotal action and propulsion force. The side sections 50 and 52 are designed in a streamlined fashion so that they have a swept-back, trans-sonic appearance. Each of the sections tapers towards its outer edge and the outer edge and forward and rearward edges of the 30 sections are tapered to a fine point to carry out the streamlined design. The rear edges 56 of the side sections extend forward and outwardly from the sides of the foot, as do the front edges 58, such rear edges being longer than the front edges. The rear edges form an obtuse angle with the foot while the front edges form an acute angle therewith.

35 As an additional factor in the thrust force of the working surfaces 14 and 16 of the fin, fences 60 on each of the side sections has been provided. The fences 60 are disposed perpendicular to the working surfaces and are disposed in laterally spaced, parallel relation on each of the side sections. The fences are disposed parallel to the axis of the foot or normal to the pivotal axis of the fin. The pair of fences on the working surface on 40 each of the side sections will space apart laterally and cooperate to form a passageway 62 for the water. In other words, the fences channel the water by forming the passageways 62 and the water is concentrated in the 45 passageways and prevented from running laterally off the fins thereby reducing the effective force of the water.

50 It is to be particularly noted that the fins are interchangeable from one foot to the other and that, through the strap and elastic adjustments, the swimming devices 55 will fit any foot.

50 Furthermore, the fins, per se, can be detached from the foot receiving means and can be held in the hands by gripping the fingers around the center connecting sections 54. Two alternate fist grips may be used, one with the center of pressure just forward of the fist grip and the other just back of it. In this way, the fins can be used with the arm stroke, without excessive twisting action on the wrist.

70 It is important that the hinge axis a-a be located adjacent the center of water pressure in order to obtain complete forward thrust and it has been found that, relative location of the center of pressure and the hinge axis and the location of the latter with respect to the ball of the foot are of importance in preventing twisting or fluttering of the fins. The positioning of the axis in relation to the 75 foot is particularly designed to place the fin at the cor-

rect angle of attack, so that each of the working surfaces is positioned at the correct angle of attack for each stroke of the two-cycle, reciprocating motion. The locating of the center of pressure immediately forward of the axis $a-a$ enables the fins to be balanced so that very little of each reciprocating stroke is wasted while the fin is swung by water pressure to its new position, that is while the fin is moved about its axis to change from one working surface to the other working surface.

While the preferred form of this invention has been described in the foregoing and illustrated in the accompanying drawings, such description and illustration are merely exemplary in nature and, since other structural forms of the invention may be realized, the scope of the invention is only limited by the appended claims.

What is claimed is:

1. A swimming device for attachment to a foot comprising a foot receiving means, a fin pivotally carried by said means and means pivotally mounting the fin to said foot receiving means for pivotal movement about an axis contained in a plane transversely intersecting the ball of a foot said fin having a center of water pressure disposed rearwardly of the toe portion of the foot and slightly forwardly of and immediately adjacent to the pivotal mounting means.

2. A swimming device for attachment to a foot comprising a foot receiving means, a fin having upper and lower working surfaces and means pivotally mounting the fin to said foot receiving means for pivotal movement in a curvilinear path of movement about an axis contained in a plane transversely intersecting the ball of a foot with the working surfaces alternately providing a thrust propulsion as the leg is moved upwardly and downwardly said fin having a center of water pressure disposed rearwardly of the toe portion of the foot and slightly forwardly of and immediately adjacent to the pivotal mounting means.

3. A swimming device for attachment to a foot comprising a foot receiving means, a fin having upper and lower working surfaces, and means mounting the fin to said foot receiving means so that the working surfaces lie in the rest position of the fin parallel to the bottom of the foot, said mounting means including a pivot mounting the fin for pivotal movement about an axis contained in a plane transversely intersecting the ball of a foot said fin having a center of water pressure disposed rearwardly of the toe portion of the foot and slightly forwardly of and immediately adjacent to the pivotal mounting means.

4. A swimming device for attachment to a foot comprising a foot receiving means, a fin having upper and lower working surfaces, and means mounting the fin to said foot receiving means so that the working surfaces lie in the rest position of the fin parallel to the bottom of the foot, said mounting means including a pivot mounting the fin for pivotal movement about an axis contained in a plane transversely intersecting the ball of a foot, with the major portion of said fin being disposed forwardly of the pivot said fin having a center of water pressure disposed rearwardly of the toe portion of the foot and slightly forwardly of and immediately adjacent to the pivotal mounting means.

5. A swimming device for attachment to a foot comprising a foot receiving means, a fin having upper and lower working surfaces, and means mounting the fin to said foot receiving means so that the working surface lie in the rest position of the fin parallel to the bottom of the foot, said mounting means including a pivot mounting the fin for pivotal movement about an axis contained in a plane transversely intersecting the ball of a foot, said fin tapering from said pivot laterally of the foot said fin having a center of water pressure disposed rearwardly of the toe portion of the foot and slightly forwardly of and immediately adjacent to the pivotal mounting means.

6. A swimming device for attachment to a foot comprising a foot receiving means, a fin having upper and

lower working surfaces, and means mounting the fin to said foot receiving means so that the working surfaces lie in the rest position of the fin parallel to the bottom of the foot, said mounting means including upstanding fixed supports on the foot receiving means and disposed on opposite sides of the foot at the ball thereof, a pivot mounting the fin to the supports for pivotal movement about an axis contained in a plane transversely intersecting the ball of a foot and disposing the fin above the instep of the foot, said fin being extended laterally from each side of the foot and having the major portion thereof disposed forwardly of the pivot said fin having a center of water pressure disposed rearwardly of the toe portion of the foot and slightly forwardly of and immediately adjacent to the pivotal mounting means and having a cut-out portion forwardly of the pivot to pass over the toes of the foot.

7. A swimming device for attachment to a foot comprising a foot receiving means, a fin having upper and lower working surfaces, and means mounting the fin to said foot receiving means so that the working surfaces lie in the rest position of the fin parallel to the bottom of the foot, said mounting means including upstanding fixed supports on the foot receiving means and disposed

on opposite sides of the foot at the ball thereof, a pivot mounting the fin to the supports for pivotal movement about an axis contained in a plane transversely intersecting the ball of a foot and disposing the fin above the instep of the foot, with the major portion of said fin being disposed forwardly of the pivot said fin having a center of water pressure disposed rearwardly of the toe portion of the foot and slightly forwardly of and immediately adjacent to the pivotal mounting means, and spring means operatively connected between the foot receiving means and the fin to retain the fin in its rest position when the foot is placed flat on the ground.

8. A swimming device for attachment to a foot comprising a foot receiving means, a fin having upper and lower working surfaces, and means mounting the fin to said foot receiving means so that the working surfaces lie in the rest position of the fin parallel to the bottom of the foot, said mounting means including upstanding fixed supports on the foot receiving means and disposed

on opposite sides of the foot at the ball thereof, a pivot mounting the fin to the supports for pivotal movement about an axis contained in a plane transversely intersecting the ball of a foot and disposing the fin above the instep of the foot, said working surfaces having perpendicular, laterally spaced, parallel flanges, axially extending normal to the axis of movement and paralleling the direction of movement to form water confining pathways said fin having a center of water pressure disposed rearwardly of the toe portion of the foot and slightly forwardly of and immediately adjacent to the pivotal mounting means.

9. A swimming device for attachment to a foot comprising a flat sole piece on which a foot is supported, a strap carried by the sole piece and adapted to fit over the instep of a foot to secure the sole piece to the bottom of a foot, supporting members upstanding from the sides of the sole piece and disposed in spaced, confronting relation, perpendicular to the ball of a foot and terminating above the instep of the foot, a fin having wings connected by a thin bridge piece, said bridge piece transversely overlying the instep of the foot and said wings laterally extending from the foot, means pivotally mounting the fin to the supporting members for pivotal movement thereof about an axis contained in a plane which transversely intersects the ball of the foot and said fin

having the major portion of its wings extending forwardly of the pivotal mounting means and said fin having a center of water pressure disposed rearwardly of the toe portion of the foot and immediately forwardly of and adjacent to the pivotal mounting means.

10. A swimming device as claimed in claim 9, wherein

said bridge piece has opposing forward and rearward concave edges for accommodation by the foot of the pivotal movement of the fin.

11. A swimming device as claimed in claim 9, wherein a strap is carried by the supporting members and is adapted to fit around the heel of the foot. 5

12. A swimming device as claimed in claim 9, wherein said wings have opposing working surfaces that taper outwardly toward the peripheral edges of the wings.

13. A swimming device as claimed in claim 12, where- 10
in said working surfaces are formed with water confining channels which extend parallel to the foot and normal to the axis of the fin and channel the water on the surfaces.
